UNITED STATES PATENT OFFICE.

NATHAN LIEBERFREUND, OF NEW YORK, N. Y.

EAR-RING FASTENER.

No. 919,041.

Specification of Letters Patent. Patented April 20, 1909.

Application filed October 24, 1908. Serial No. 459,345.

To all whom it may concern:

Be it known that I, NATHAN LIEBERFREUND, a citizen of the United States, residing at New York city, Manhattan, county 5 and State of New York, have invented new and useful Improvements in Ear-Ring Fasteners, of which the following is a specification.

This invention relates to an ear ring 10 fastener which is of simple construction, may be readily manipulated, and is not liable to become accidentally opened.

In the accompanying drawing: Figure 1 is a side view of an ear ring provided with 15 my improved fastener; Fig. 2 a side view of the male member of the fastener; Fig. 3 an enlarged cross section on line 3—3, Fig. 1; Fig. 4 a longitudinal section of the female member on line 4—4, Fig. 3; Fig. 5 a front 20 view of said female member, and Fig. 6 a longitudinal section of a modification of the female member.

From the setting or other ornamentation 10 of an ear ring extends a stem 11 provided 25 with a bit 12 set back from the end of the stem, said bit and stem constituting the male member of the fastener.

The female member comprises a back plate 13 having a central opening into which is 30 fitted a tubular sleeve 14 which projects forwardly from the plate. Sleeve 14 is slotted longitudinally, as at 15, to accommodate bit 12, which may be passed back of plate 13 through a radial slot 16 thereof, 35 said slot communicating with the central opening of the plate. From the back of plate 13 projects a bail or holder 17 carrying an axially movable tapped socket 18 which is engaged by a threaded plunger 19 adapted 40 to be lowered with its operative end against plate 13. Plunger 19 is preferably so positioned that when lowered it will engage slot 16, (Fig. 3). An abutment 20 may be formed on back plate 13 to limit the rotation 45 of stem 11.

To close the fastener, stem 11 is passed through sleeve 14 until its bit 12 arrives back of plate 13. A turn is next given to the stem, so that the bit is carried against abutment 20. Finally, plunger 19 is screwed 50 down to obstruct the return of the bit through slot 16 and thereby securely close the fastener.

To open the fastener, plunger 19 is raised and stem 11 turned until its bit 12 becomes 55 aligned with slot 16, after which the stem may be readily withdrawn through sleeve 14.

In Fig. 6, socket 21 of bail 17 has a tubular bore for the reception of a cylindrical pin or plunger 22 having a stop 23 and held in 60 position by frictional contact with the socket or otherwise.

It will be seen that my improved fastener permits the ready attachment of the ear ring 65 to the lobe, that it may be easily manipulated, and that it securely locks the ear ring against accidental opening.

I claim:

In a device of the character described, a male member comprising a stem and bit 70 extending laterally therefrom, combined with a female member comprising a plate having a perforation adapted for the passage of the stem and bit, said stem and bit adapted for rotation after entering said plate, a 75 holder on the back of said plate, a socket on the holder and an axially movable plunger engaging the socket and adapted to be lowered against the plate in the path of rotation of the bit to thereby obstruct the withdrawal 80 of the bit through the perforation of the plate.

Signed by me at New York city, (Manhattan,) N. Y., this 23d day of October, 1908.

NATHAN LIEBERFREUND.
